CLAIM

The ornamental design for a combined tiller arm and control panel for an outboard motor, substantially as shown and described.

DESCRIPTION

FIG. 1 is a top, front and left side perspective view of a combined tiller arm and control panel for an outboard motor showing my new design;

FIG. 2 is a top plan view thereof;

FIG. 3 is an enlarged rear elevational view thereof;

FIG. 4 is a right side elevational view thereof;

FIG. 5 is a front elevational view thereof; and

FIG. 6 is a bottom plan view thereof.

The various connecting cables are shown broken-away in the views to indicate indeterminate length.
